COMBINED CHEST OF DRAWERS AND CLOTHES RACK

Laurence Heftel, Palm Beach, Fla.

Application April 17, 1952, Serial No. 19,368

Term of patent 14 years

(Cl. D33—8)

To all whom it may concern:

Be it known that I, Laurence Heftel, a subject of the Queen of England, residing at Palm Beach, county of Palm Beach, State of Florida, have invented a new, original, and ornamental Design for a Combined Chest of Drawers and Clothes Rack, of which the following is a specification, reference being had to the accompanying drawing, forming a part hereof.

Fig. 1 is a perspective view of a combined chest of drawers and clothes rack embodying my new design, illustrating the top, front and one side thereof.

Fig. 2 is a perspective view showing the top, back and other side thereof, and

Fig. 3 is an elevational view showing one side thereof.

I claim:

The ornamental design for a combined chest of drawers and clothes rack, as shown.

LAURENCE HEFTEL.
